UNITED STATES PATENT OFFICE.

WALTER L. CONWELL, OF MONTCLAIR, NEW JERSEY, ASSIGNOR TO ELLCON COMPANY,
OF NEW YORK, N. Y., A CORPORATION OF NEW YORK.

SLIDABLE METALLIC DOOR.

1,270,011.

Specification of Letters Patent. Patented June 18, 1918.

Application filed December 4, 1914. Serial No. 875,482.

To all whom it may concern:

Be it known that I, WALTER L. CONWELL, residing at Montclair, New Jersey, and being a citizen of the United States, have invented certain new and useful Improvements in Slidable Metallic Doors, of which the following is a full, clear, and exact description, such as will enable others skilled in the art to which it appertains to make and 10 to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings:

Figure 1 is a side elevation of my improved door, the weather strip for the upper edge thereof being omitted.

Fig. 2 is a similar view on an enlarged scale, horizontal and vertical intermediate portions being broken away.

Fig. 3 is a vertical central section through the door, taken on line 3—3, of Fig. 1.

Fig. 4 is a horizontal section taken through the middle and lower panels of the door, as indicated by line 4—4, of Fig. 1, the 30 central portion of the door being broken away.

Fig. 5 is a fragmentary elevational view of the upper left hand corner of the upper panel, as viewed from the reverse side of the door, and shows a portion of the glass-retaining means.

Fig. 6 is a similar view, but with the glass-retaining means removed.

Fig. 7 is a side elevation of one of the 40 corner pieces of the molding for the glass panels.

Fig. 8 is an end elevation thereof.

Fig. 9 is a fragmentary side elevation of the upper portion of the door showing the 45 weather strip for the upper edge in place.

Fig. 10 is a fragmentary view of a corner of the door, illustrating the attachment of the door side sheets to the door edge and window outlining members.

Fig. 11 is a perspective view of a portion 50 of one of the vertical door edge binders.

Fig. 12 is a side elevation of a modified form of door, a portion of the same being broken out; and

Fig. 13 is a horizontal section, taken on

line 13—13 of Fig. 12, through the upper and lower panels of the door, the central portion of which is removed.

My present invention relates to metallic doors, which while readily adaptable to general architectural purposes, are particularly suitable for use in railway cars. An object is to provide a door, which shall be constructed of incomplex parts, relatively few in number and kind. Most of said 60 parts are characterized by their ability to be kept in stock, and merely cut to size to give the desired dimensions to any given door.

It is further purposed to so correlate the side sheets of the door with the door edge 70 and panel outlining frame as to give great strength and rigidity to the door, and to so unite these parts as to guard against their accidental separation.

As it is desirable that the door edges shall 75 each bear an appropriate relation to the corresponding portion of the structure forming the door opening, and in view of the diverse conditions present in the various portions of the latter, it is purposed that the 80 door edge outlining frame shall be furnished with suitable means of attachment for harmonizing complementary edges.

Simple but effective means for retaining 85 removable glass or other panels are supplied, and are so formed as to contribute to the attractive appearance of the door.

Another object is to include effective reinforcements for stiffening the door and providing means of attachment for locks, 90 door operating apparatus, and sundry accessories.

Exclusion of air currents or drafts when the door is closed is also made possible by the construction of the door, and other features not specifically mentioned, but appearing hereinafter, are all a part of the present invention.

Referring to the drawings, 1 indicates the side sheets of the door, which may be of 100 steel, though any other suitable material is substitutional, and said side sheets are preferably pressed to present a conventional appearance. In Fig. 1, each side sheet pressing 1 simulates a pair of stiles 2, a top rail 105 3, a bottom rail 4, an upper intermediate rail 5, a lower intermediate rail 6, and a lower panel 7.

Between the stiles 2 and the top rail, upper intermediate and lower intermediate 110

rails, 3, 5 and 6, respectively, are panel openings adapted to receive glass or other panels 8, hereinafter more fully referred to.

Outlining the door side sheets 1 and the 5 openings for the glass panels 8, are depressed flanges 9, those portions of said side sheets 1, which connect flanges 9 with the side sheet portions that lie in the plane of the stile and rail outer surfaces, forming 10 shoulders. The space between the flanges 9 of the sheets 1, which latter are spaced transversely of the door, is therefore narrower than the space between the stile and rail portions of said sheets.

15 Bearing against the inner sides of those shoulders formed in producing the flanges 9 which outline door sheets 1, are channels 10, preferably of drawn steel and provided with Z-shaped flanges. Said Z-shaped 20 flanges of each channel 10 conform to the configuration of the cross section of the outer borders of side sheets 1 from a point within the stile or top or bottom rail portions to the outer edge of the flange 9, extending 25 outwardly from that point, and said flanges are connected at their inner ends by the web of the channel.

The Z-shaped channel flanges, in addition to conforming to the borders of side sheets 30 1, contact therewith, and those portions coincident with flanges 9 are secured thereto, preferably by spot-welding, as indicated by the shaded spot *a* in Fig. 10.

Channels 10 extend substantially the 35 length of the sides of side sheets 1, to which they are applied, and may be mitered or not at their points of intersection, forming a rigid stiffening and strengthening door edge-outlining frame.

40 The openings for the removable panels 8 are similarly reinforced by a panel-outlining frame, comprising channels 11 which may be duplicates of channels 10, except in respect to the upper intermediate rail 5. 45 The latter being common to the upper and intermediate panels, and in each side sheet 1 being provided with upwardly and downwardly projecting flanges 9, a simple channel 12 is employed to connect the upwardly 50 extending flanges of the pair of side sheets, and another channel 12 with reversely directed flanges connects the downwardly projecting flanges 9 of said side sheets 1, as shown in Fig. 2 and 3.

55 As illustrated, the vertical channels 11 may be continuous from the top of the upper panel to the bottom of the intermediate panel, and channels 12 associated with the upper intermediate rail may extend between 60 and about the same. In this manner the vertical channels 11 will not be weakened by cutting, though where considered preferable, channels 12 may be mitered into vertical channels 11, as are the intersecting horizontal channels 11.

The inwardly depressed portions of the flanges of all of the channels 11 and the flanges of channels 12 are spot welded to the inner flanges 9 of side sheets 1, as partially indicated at *b*, in Fig. 10.

To one of the door sheets 1 is secured a number of preferably vertically disposed strips 13 of U-shaped cross section, each having one of its flanges free, and fastened to the other sheet 1 are other similarly disposed strips 14, each having a free flange bent into an inner plane to form with the inside of one panel 7 sockets for the reception of the free flanges of the U-shaped strips. Before the welding of the door edge 80 and panel-outlining frames to both side sheets 1, the said sheets are moved parallel to each other to cause the U-shaped strips 13 to enter the sockets referred to and lap strips 14. Thus, the lower part of the door may 85 be strongly reinforced.

From the foregoing it is evident that the door is provided with a pair of spaced but conterminous side sheets, supplied with openings for removable panels, and that 90 said side sheets are preferably connected together by the interposition of door edge and panel-opening edge outlining frames. It is also apparent that the welding of the flanges of the outlining frames to the flanges of the 95 door side sheets and the reinforcing of panel 7 produces a substantial basic door structure. From the foregoing and the drawings, it is clear that said basic door structure does not constitute a complete door 100 structure, and door-edge-forming members are applied to the channels 10 of said door edge-outlining frame to form component parts thereof, to close the sides of said channels and to provide the door with suitable 105 door edges. These edge-forming members are hereinafter referred to as the door hanger, edge-forming strips, guide strip, finger guard and finishing strip. Channels 11 and 12 of the panel-opening edge outlining frame are closed by molding frames 110 complementing said channels 11 and 12.

Fitted around each opening for a removable panel is a molding frame, by choice constructed of pressings suitably formed 115 into an integral unit, as by welding them together. Said molding frame pressings are illustrated as comprising top, bottom and side strips 15 of less length than the respective sides of the opening they partly 120 outline, and corner pieces 16 adapted to connect the juxtaposed ends of adjacent molding strips, thus completing the circuit of the molding frame.

Strips 15 and corner pieces 16 each have 125 spaced parallel flanges arranged to lap and contact with those flanges 9 of the side sheets 1 which outline the panel opening in the basic door structure into which the molding frame is introduced. Extending in- 130

wardly from their flanges, the components of the molding frame are beveled on one side to a desirable depth, from which point to their opposite flanges they are of angular 5 cross-section.

The beveled portion of each corner piece 16 may be provided with appropriate radii, as shown, to improve the lines of the door, but, where this refinement is not cared for, 10 the molding strips 15 may run the entire lengths of their respective sides and be mitered, the corner pieces 16 being in such case omitted.

That portion of each molding frame 15 which is of angular cross-section forms, on the side of said frame opposite that having the bevel, a depression 15^a for the reception of the glass or other removable panel 8 and cushioning strips 17, which latter may well 20 be composed of felt, and be of U-shaped or other cross-section to embrace the edges of the removable panel 8, which it surrounds. It is advantageous to have this depression rectangular in form and devoid of rounded 25 corners that ordinary panes of glass may be inserted.

The flanges of the corner pieces 16, of which are adjacent the depression, may be slit, as along the diagonals intersecting the 30 vertices of their inner and outer right angles, to facilitate the putting of the molding frame into place, Fig. 6 disclosing one way of doing this.

To conform to good manufacturing practice, the strips 15 are pressed in a well-known and simple manner as units, but the corner pieces 16, as shown in Figs. 7 and 8, are economically produced in two pieces 16^a and 16^b, the former being provided with a 40 lip 16^c, which laps the inwardly extending flange of part 16^b, and is spot welded thereto, as indicated at c in Fig. 7.

Strips 15 and corner pieces 16 are butt welded, or welded transversely of their 45 joints, as by the oxyacetylene method, resolving all of the molding frame parts into a unitary structure. See places indicated by d, particularly in Figs. 2 and 6.

Those flanges 15^b of the strips 15 and corners pieces 16, of the molding frame, which are adjacent the outer opening of the depression 15, are in a plane inset from the outer surfaces of the stiles and rails, and with the shoulders 1^a of said stiles and rails 55 form a second depression.

Within this second depression is placed a panel-retaining frame, comprising substantially flat retaining strips 18 and corner pieces 19, the cross sections of which are 60 shown to be rectangular and of materially greater width than thickness. It is, however, evident that these members, and also those of the molding frame, may partake of other sections than those shown, and, 65 when the removable panels 8 have a suit-

able transverse disposition, be given the contour of any classical or other molding.

Corner pieces 19 of the retaining frame are usually supplied with an arc on their inner sides, corresponding in dimensions to 70 those of the lesser radii of the beveled corner pieces of the molding frame, and the horizontal or cross retaining strips 18 are ordinarily welded, as at e in Fig. 5, to corner pieces 19, but the upright retaining 75 strips are not so united. Greater convenience in applying and removing the retaining frame is thereby attained through the reduction of the number of separate parts.

Removable panels 8, their cushioning 80 strips 17 and the retaining frame just described are firmly held in place by screws 20, which pass through strips 18 and corner pieces 19 of the retaining frame, the contiguous flanges of the molding frame, the 85 flanges 9 which contact with the latter and into the lapping portions of the Z-shaped flanges of channels 11, which channels have sufficient thickness to be tapped to receive the screws. Screws 20 are usually of the 90 type known as French screws, as are all the screws used in the door which are visible, this adding to the finished appearance of said door.

The doors illustrated in the drawings being of the sliding type, a suitable hanger is provided. As shown in the forms of Figs. 1 and 12, it may comprise a bar 21 practically co-extensive with the width of the door, and having approximately its lower half inserted 100 between the upwardly extending, more narrowly spaced, portions of the Z-shaped flanges of the channel 10 paralleling the upper edge of the door. At the same altitude, and on reverse sides thereof, the 105 bar 21 is provided with raceways 22, shown as running the length of the bar. The raceways are designed to receive properly supported and retained balls, arranged on opposite sides of hanger bar 21 to furnish an anti-friction support for the door.

Angular-shaped edge-forming strips 23, also substantially co-extensive with the width of the door, parallel the upper edge of top rail 3 and extend thereabove, and 115 each has a horizontal flange, the edge of which abuts one side of bar 21. Edge-forming strips 23 are located on opposite sides of said hanger bar and preserve the usual rectangular cross section of the top portion 120 of the door.

Countersunk screws 24 pass alternately through both edge-forming strips 23 on opposite sides of the door, filler pieces 25, which are interposed at the screws between 125 strips 23 and flanges 9 of one side sheet 1, said flanges 9, the flange of the top horizontal channel 10, the inserted part of hanger bar 21, the other flange of channel 10, the flange 9 of the other side sheet 1 and 130

into the filler on the opposite side of the door. Hanger bar 21 and the other parts comprising the top edge of the door are thus firmly bound together.

- 5 As seen in Figs. 3 and 9, the upper edge of one side of the door is provided with a suitable weather strip comprising a metallic holding strip 26, secured, as by welding, to and along the top edge of the door, and a flexible strip 27, of such material as carpet.

The bottom edge of the door is furnished with a guide strip 28 co-extensive with the bottom rail 4. Said guide strip has vertically arranged flanges which lap the lowermost flanges 9 of both side sheets 1, screws 29 passing through said guide strip flanges, the specified flanges 9 and the Z-shaped flanges of the bottom channel 10 of the door edge-outlining frame, securing guide strip 28 in place. The latter also possesses a downwardly projecting tongue 28^a adapted to slide in a groove in the usual threshold plate (not shown).

When the door is used in a railway car employed in a subway or traction service, where hasty entrances and exits by passengers is customary, there is an ever-present danger of impulsive people attempting to leave or enter the car as the door is closing. Far too frequently this results in the hand of the eager person being caught between the edge of the door and its jamb, or between the edges of companion doors, where a pair are used. And, if said person is on a platform, he is in imminent peril of being forced to run with the car, with the ultimate possibility of being thrown and sustaining serious injuries or loss of life.

To avoid such contingencies, the outer vertical edge of the door is supplied throughout its length with a finger guard 30 of relatively soft and compressible material. This finger guard may easily be constructed, say, of rubber sheet bent to have a U-shaped cross section, and with the borders of its open side arranged each to lap one of the flanges 9 which outline the side sheets 1 along this side of the door.

Clamping strips 31, each with an inturned flange along its inner edge adapted to abut the shoulder which produces the line of demarcation between the outer edge of the adjacent stile 2 and its flange 9, are shown as continuouslylapping said open-side borders 55 of the finger guard 30.

The outer edges of strips 31 are improved by being bent to produce a longitudinal bead on each, so protecting the adjacent material of the finger guard 30 from abrasion, when the latter is displaced by compression. Screws 32, preferably of the French type and on each side of the door, pass through clamping strips 31, one edge of finger guard 30 and the Z-shaped flange of the vertical channel 10 paralleling this edge of the door,

these parts being firmly retained in place thereby.

Within, and near the upper and lower extremities of the finger guard 30, the latter is reinforced by resilient means, as blocks of 70 rubber 33. The positions of said rubber blocks are away from any hand or clothes-catching locations, and said blocks take up the jar incident to closing the door.

Along the other or inner vertical edge of 75 the door, a finishing strip is applied, and it comprises an outwardly exposed channel member 34 and an internal flanged U-shaped channel 35, both shown as equal in length to the door height, though channel 35 may 80 comprise a plurality of short pieces united to channel 34.

The outer or exposed channel member 34, preferably of drawn steel, and the free borders of its flanges are reversely bent inwardly at an acute angle to the remainder of the flanges, and the internal U-shaped channel member 35 is a pressing, by choice, and its flanges are outturned and adapted to engage the transverse portions of the Z- 90 shaped flanges of channel 10, paralleling this edge of the door. See Fig. 4.

Both channel members 34 and 35 are preferentially intermittently united by spot welding, as indicated at 9 in Fig. 11, resulting in the equivalent of a single member.

In applying this finishing strip, one of its ends is so registered with an end of its associated vertical channel 10 that said strip may be slid into place, whereupon it becomes interlocked with the specified channel 10. The outturned flanges of internal channel member 35 lap the transverse portions of the Z-shaped flanges of channel 10, the outer edges of said flanges and of flanges 9 of the side sheets 1 abut the web of channel member 34, and the deflected portions of the flanges of channel member 34 bear against said flanges 9 of side sheets 1 and the shoulders outlining the outer edge of stile 2 on 110 this side of the door.

The fit of the finishing strip to the basic door structure is such that relatively considerable force is necessary to apply it, and the elasticity of the metal of which it is composed is sufficient to allow its application to said basic door structure without undue difficulty, operating, however, to produce enough friction to securely retain it in place.

Applied to the exterior surface of the web portion of channel member 34 is a weather strip 36, which may be of felt, of a length equal approximately to the door height, and held in place by a clamping plate 37, screws 38 and reinforcement pieces 39 tapped to receive said screws. Weather strip 36 is pliable and its free ends, while normally extensible transversely of the door are adapted to conform to vertical stop plates 40, shown 130

in dot and dash lines in Figs. 4 and 13, and preferably attached to the car framing (not shown).

Wherever fixtures, as door-operating mechanism attachments, tripping devices, emergency bolts, locks and wearing strips, are not attachable to such substantial parts as, for example, channels 10 or 11, other reinforcing plates 41, tapped, when necessary, 10 to receive screws or bolts are provided.

The form of door shown in Figs. 12 and 13 is constructed much like that illustrated in the preceding figures, except that a single glass or removable panel is shown, and both 15 vertical edges of the door are furnished with finishing strips comprising channel members 34 and 35, the finger guard being omitted.

It is apparent that I have devised a door easy and inexpensive to manufacture, composed principally of parts which may be produced in general lengths and cut to size 20 for any particular door, and which is thoroughly durable and attractive in appearance, and possessing the numerous advantages hereinbefore set forth.

It should be clearly understood that the door edge-outlining frame, and even the panel opening outlining frame, are not necessary to the construction of a door intended 30 for certain uses, but when the door is likely to receive hard and careless usage, the introduction of these frames into such a door is necessary to insure great prolongation of its life.

35 After assemblage, the door is rendered rust-proof by a coating of suitable paint, or other substance, which also fills the cracks between separate parts, and excludes water and moisture from the interior.

40 What I claim is:

1. In a metallic door, door edge and panel-opening frames each with open bounding edges, door side sheets on opposite sides of said frames connected to and connecting 45 both frames and provided with panel openings, attachment means on each frame, complementary door edge-forming members and a panel-receiving member secured, respectively, to the attachment means of the first 50 and second mentioned frames, said door edge-forming members being constantly maintained inseparable from said door edge frame in a direction transversely thereof, a panel, and retaining means therefor.

55 2. In a metallic door, door edge and panel-opening frames, each comprising separate fitted strips opposed to the strips of the other frame, said strips having spaced flanges, the flanges of the strips in one frame being oppositely directed to those of the opposing strip of the other frame, opposed unitary door side sheets connected to and connecting both frames, complementary door edge-forming members and a panel-receiving 60 member secured to and connecting the

flanges of the first and second mentioned frames, respectively, to close the space between said flanges, a panel, and retaining means therefor.

3. In a slidable metallic door, an upper 70 door edge frame member provided with spaced upwardly directed flanges having depressed borders, door side sheets on opposite sides of said frame member secured thereto and a door edge member projected between the depressed border portions of said spaced flanges and secured thereto and having a longitudinally grooved portion beyond the outer edges of said flanges.

4. In a slidable metallic door, a lower 80 door edge frame member provided with spaced downwardly extending flanges having depressed borders, door side sheets on opposite sides of said frame member secured thereto, and a door edge-forming member 85lapping and secured to the depressed borders of said flanges and bottom borders of said side sheets, embracing the latter, closing the space between said flanges and extending therebelow with reduced width.

5. In a metallic door, a door edge frame channel having a web and spaced flanges, door side sheets wholly external to said channel and extending with the flanges thereof toward a door edge, said sheets and flanges being inset intermediate the width of the flanges to form external and internal shoulders, and a door-edge-forming strip interlocked with said shoulders against separation from said channel transversely 95 thereof.

6. In a metallic door, door side sheets having inset borders disposed about panel openings and extending away from the portions from which they are inset in planes 100 parallel therewith, panel opening-outlining and panel-receiving frames each with flanges oppositely disposed to those of the other frame, the flanges of both frames being combined with and parallel to the inset 105 side sheet borders.

7. In a metallic door, a door edge frame comprising outwardly opening channel strips with partially depressed flanges having internal and external shoulders, door 115 side sheets having shoulders and depressed flanges, the latter lapping and being secured to the depressed portions of said channel flanges, a door edge-forming finishing member closing one of said channel strips and comprising an external channel member with inturned flanges adapted to bear against side sheet shoulders and flanges and an internal channel member united to said external channel member and projecting 120 within said channel strip to engage and be retained by the internal shoulders thereof, and other edge-forming members closing 125 the other channel strips.

8. In a metallic door, a door edge frame 130

- having open edges about its perimeter and outstanding flanges with depressed portions and internal and external shoulders, door side sheets conterminous with and conjoined 5 to said frame and provided with depressed flanges and shoulders conformate with those of said frame, a complementary door edge-forming finishing member closing an open edge of said frame and comprising 10 united external and internal members each having portions adapted to coöperate with each other and said frame internal and side sheet external shoulders and flanges to interlock said edge-forming member with 15 said frame, and other edge-forming members closing the other frame open edges.
9. In a metallic door, opposite door side sheets forming registering panel openings, and a molding frame having corner-pieces 20 comprising two parts, each part having a flange secured to the panel-opening-outlining border of one of said side sheets, both parts extending toward each other to meet in a plane intermediate and parallel to their 25 spaced flanges, one part having a liplapping and united to the other part.
10. In a metallic door, an upper door edge frame member provided with upwardly directed flanges having depressed portions 30 and shoulders, door side sheets disposed on opposite sides of said frame member and having flanges and shoulders conformate with those of said frame member, a top door edge-closing member partly pocketed 35 within said flanges and extending thereabove, cover strips inclosing said side sheet flanges and shoulders and having portions parallel with and spaced from said side sheet flanges, filling pieces disposed between 40 the latter and said cover strip portions that are spaced from said sheet flanges and means securing the parts together.
11. In a metallic door, a door side sheet depressed about a panel opening, a frame 45 having a panel-receiving depression, a panel positioned therein, and a panel-retaining frame set into the depressed portion of said side sheet, bearing against said panel-receiving frame and having uniform thickness whereby its outer face remains flush 50 with the undepressed portion of said side sheet.
12. In a metallic door, door edge and panel-opening frames, the former having 55 open edges about its perimeter and the latter having flanges directed toward the central portion of the door, integral door side sheets formed to simulate the characteristic parts of door sides connected to opposite sides 60 of said frames, door edge-forming members closing said open edges and a panel-receiving frame lapping and connected to said flanges.
13. In a metallic door, a door edge frame, 65 a panel-opening frame having spaced par-
- allel flanges delineating a panel-opening, door side sheets arranged on opposite sides of said frames and secured to each frame, said side sheets having panel openings and simulating the stiles, rails and part of the 70 panels of a door, a panel-receiving frame connected to said parallel flanges and closing the space therebetween, a removable panel and retaining means therefor.
14. In a metallic door, a door edge frame 75 and a panel-opening frame, door side sheets arranged on opposite sides of said frames and secured to each frame, each side sheet having a panel opening and simulating the stiles, rails and part of the panels of a 80 door, a removable panel, means holding the same within the panel-opening frame, and separate but interlocking linear stiffening members continuously connecting the simulated panels of said side sheets substantially 85 throughout one of their dimensions.
15. In a metallic door, a panel-opening frame having inwardly directed flanges, door side sheets suitably connected at their outer borders and having panel openings 90 and flanges about said openings external to said panel-opening frame, said latter flanges lapping and being united with said frame flanges, a molding frame comprising flanges lapping said side sheet flanges, a 95 molding-contour portion and a panel-receiving depression conforming to said panel-openings; a removable panel, a retaining frame therefor, and means securing the retaining frame in position.
16. In a metallic door, having a buffer edge, a door edge channel having flanges with depressed borders, opposite door side sheets paralleling said flanges along their exterior sides only, and a resilient door 105 edge member closing the space between the channel flanges and having borders lapping the depressed portions of said channel flanges and side sheets.
17. In combination in a metallic door, 110 door edge framing members comprising channels each having an inner web portion and outwardly disposed relatively Z-shaped flanges and door side sheets provided with edge flange portions lapping, conforming to 115 and being secured to said Z-shaped flanges.
18. In combination in a metallic door, 120 door edge framing members comprising channels each having an inner web portion and outwardly disposed shouldered flanges, door side sheets provided with shouldered flange portions lapping, conforming and being secured to the flanges of said channels and a door hanger member connected to said flanges.
19. In combination in a metallic door, 125 door edge outlining frame members having flanges of Z-shape in cross section and a connecting web portion, a door hanger member extending between some of said flanges and 130

- side sheets lapping said door hanger member and being secured thereto.
20. In combination in a metallic door, connected side sheets spaced apart to provide 5 stiles and rails of predetermined thickness and having outlining flange portions of less thickness, and an outlining frame of channel form in cross section comprising outwardly disposed shouldered flanges interlocked with 10 and secured between the flange portions of said side sheets.
21. In combination in a metallic door, spaced and flanged side sheets forming stiles and rails of predetermined thickness and an 15 outlining flange portion of less thickness and an outlining frame of channel form in cross section comprising parallel outwardly disposed flanges which are interposed between the flanges of said side sheets, all of said 20 flanges having shouldered portions interlocking when in assembled relation.
22. In a metallic door, a channel member in juxtaposition to the top of the door and having spaced flanges with depressed 25 borders, door side sheets on opposite sides thereof having borders conformed to said flanges, a channel-closing member extending above the latter, angular strips parallel with the flange-conforming borders of said sheets 0 and having portions spaced therefrom, fillers between said side sheet borders and angular strips, and means securing the parts together.
23. In a metallic door, a door edge channel 5 member provided with spaced flanges having depressed borders and external and internal shoulders, door side sheets on opposite sides of said channel member having portions conformatte with said flanges, and a 0 channel-closing member comprising united external and internal members gripping said channel member flanges and conformatte side sheet portions.
24. In a metallic door, a door edge channel 5 member provided with flanges having inset outer portions and intermediate shoulder-forming portions, door side sheets on opposite sides of said channel member having outer border portions paralleling the outer 0 faces of said channel member flanges, and a channel-closing member comprising external and internal channel members, the former having portions bearing against said side sheets and the latter against said door edge 5 channel member at the shoulder-forming portions of the side sheets and door edge channel.
25. In a metallic door, a door edge construction comprising a plurality of channel 0 members, each provided with flanges, some of said channels being permanently united,
- door side sheets on opposite sides of another of said channels and extending with the flanges thereof to the flanges of one of said permanently united channels, between the 65 flanges of both the permanently united flanges and toward the web of the first specified of said permanently united channel members.
26. In a metallic door, a door edge channel 70 provided with spaced flanges having inset outer borders and shoulder-forming portions, door side sheets on opposite sides of said channel having inset edge border portions and shoulder-forming portions, and a 75 channel-closing member comprising permanently united external and internal channels the former having flanges rebent to bear against said side sheet shoulder-forming portions and the latter extending between 80 the spaced flanges of said door edge channel and having flanges bent to engage said shoulder-forming portions of said door edge channel.
27. In a metallic door, a molding frame 85 for a panel opening comprising spaced attachment flanges having substantially parallel opposing sides, a molding contour portion and a portion of angular cross section together connecting said spaced flanges without entering therebetween, one of said flanges and said portion of angular cross section forming a Z-shaped subdivision in the cross section of said molding frame.
28. In a metallic door, structure forming 90 the door except its edges and provided with door-edge-receiving portions parallel to the various door edges, said portions at the different door edges being of uniform construction, different door-edge-forming members 95 having differently formed portions fitting the uniform receiving-portions of said structure, and means locking the door edge members to said structure.
29. In a metallic door, structure forming 100 the door except its edges and provided with uniformly fashioned door-edge-receiving portions parallel with different door edges, different door-edge-forming members having differently constructed portions for interconnection with the uniform receiving-portions of said structure, and means preserving the interconnection of said structure and door edge members permitting the 105 removal of said members.
- In witness whereof I have hereunto set my hand in the presence of two witnesses.
- WALTER L. CONWELL.
- Witnesses:
- H. B. CHAMBERLAIN,
JOSEPH C. DUNN.
